UNITED STATES PATENT OFFICE.

STACY B. HASELTINE, OF CHICAGO, ILLINOIS, ASSIGNOR TO WILLIAM H. MINER, OF CHAZY, NEW YORK.

RAILWAY-CAR ROLLER SIDE BEARING.

1,181,879.

Specification of Letters Patent.

Patented May 2, 1916.

Application filed April 5, 1915. Serial No. 19,354.

To all whom it may concern:

Be it known that I, STACY B. HASELTINE, a citizen of the United States, residing at Chicago, in the county of Cook and State of Illinois, have invented a certain new and useful Improvement in Railway-Car Roller Side Bearings, of which the following is a full, clear, concise, and exact description, reference being had to the accompanying drawings, forming a part of this specification.

This invention relates to improvements in railway car roller side bearings.

An object of the invention is to provide a roller side bearing for railway cars consisting of few parts, easily manufactured and readily assembled, and spring means for automatically returning the roller to its central normal position after each actuation thereof, which spring means performs its function through the intermediary of a member in which the roller has its bearings.

The invention furthermore consists in the improvements in the parts and devices and in the novel combinations of the parts and devices, as herein shown, described or claimed.

In the drawing forming a part of this specification, Figure 1 is an end elevation of portions of a car body bolster and a truck bolster showing my improvements in connection therewith. Fig. 2 is an enlarged vertical sectional view taken on the line 2—2 of Fig. 1 and Fig. 3 is a vertical sectional view taken substantially on the line 3—3 of Fig. 2. Fig. 4 is a view similar to Fig. 3 illustrating another embodiment of my improvement.

In said drawing, 10 denotes the body bolster and 11 the truck bolster of a car pivotally connected in the usual manner and between which is mounted my improved bearing designated generally by the reference A. As shown, said bearing is attached to the truck bolster, but as will be apparent to those skilled in the art, it may be attached to the body bolster, if desired.

The improved roller bearing A comprises a base casting 12 riveted or otherwise suitably secured to the truck bolster, said casting 12 being provided on its upper face with inserted roller tread plates 13 made of steel or other suitable material adapted to resist wear. Extending longitudinally on the

sides of said casting 12 are ribs or tongues 14 which coöperate with correspondingly shaped grooves 15 formed on the inner sides of depending flanges 16 cast integral with a second casting 17. By means of the tongue and groove arrangement above described, the casting 17 is permitted to slide back and forth on the casting 12 and is prevented from vertical or transverse removal therefrom. The casting 12 is centrally slotted as indicated at 18 and in this slot reciprocate 65 depending arms or abutments 19—19 cast integrally on the ends of the casting 17. The casting 12 is also hollowed out centrally as indicated at 20 and mounted therewithin is a longitudinally arranged coil spring 21 70 having spring followers or caps 22—22 at the ends thereof, which caps 22 are limited in their outward movement by means of shoulders or stops 23 formed within the recess 20. Each of the spring caps 22 is provided with an inwardly extending boss 24 on which an end of the spring is carried, thereby supporting the latter. At the bottom of the recess 20 and on each side thereof, the casting 12 is provided with supporting 80 guideways 25 for the spring caps or followers 22 to reciprocate upon. As clearly appears from Fig. 2, the depending arms 19—19 of the casting 17 are normally in engagement with the spring followers 22 so 85 that the casting is thereby centered with respect to the base casting 12. The casting 17 is provided with a substantially rectangular centrally located opening 26 in which is mounted an anti-friction roller 27, the latter being supported on a shaft 28 extending through the roller and having its ends mounted in suitable recesses in the side walls of the casting 17. To minimize the wear 90 between the roller 27 and supporting shaft 28, a bushing 29 may be employed. The ends of the shaft 28 are flattened as indicated at 30 and the surrounding metal of the casting 17 hammered or peened thereagainst to prevent the shaft from rotating 100 and also from coming out.

The diameter of the roller 27 is such that it normally lifts the casting 17 slightly from the top of the casting 12. In operation, pressure being applied to the roller 27 from 105 the thrust plate of the body bolster, the roller will roll upon the tread or wear plate 13 and the casting 17 in which the roller is

mounted will move in the direction of rotation of the roller, thus compressing the spring 21.

As clearly shown in the drawing, the 5 plates 13—13 are beveled at their ends as indicated at 31 and the length of said plates is such that the anti-friction rollers will always bear thereupon within ordinary limits of relative movement between the two bolsters. However, upon an abnormal amount 10 of relative movement between the two bolsters the anti-friction rollers will pass off of the plates 13—13 and the casting 17 will fall until it bears upon the casting 12. During 15 this position, anti-friction means to permit excessive radiation of the bolsters is provided by the anti-friction rollers, the latter turning about and being supported on their own shafts and without translation bodily. Upon release of the pressure, the 20 springs will return the rollers to their normal position, the inclined ends 31 facilitating the lifting of the roller and the casting in which it is carried.

25 In the construction shown in Fig. 4, a base casting 112 is provided, the same having a tread plate insert 113 on which rolls the roller 127. The latter is mounted on a shaft 128 supported and carried by a reciprocating casting 117 having a tongue and groove in slidable engagement, 114 and 115, with the casting 112. In this case the casting 112 has two spring chambers 120—120 located on the sides thereof in which are 30 mounted springs 121—121. These are engaged by the extensions 119 on the depending side arms of the casting 117 and abutments or stops 123 are formed integrally on 35

the casting 112 at the ends of the chambers 120. The operation of this arrangement is 40 substantially the same as that above described for the construction illustrated in Figs. 1 to 3.

I claim:—

1. In a roller side bearing for railway 45 cars, the combination with a base casting, of a second casting slidably mounted thereon, means automatically operable for positioning said slidable casting centrally of the base casting, said slidable casting having a 50 centrally disposed opening in the top thereof, an anti-friction roller within said opening, and a journal on which said roller is carried, said journal having its ends mounted in the side walls of said slidable casting. 55

2. In a roller bearing for railway cars, the combination with a base casting having a roller tread surface, of a second casting slidably mounted on the base casting, spring means for centering the slidable casting on 60 the base casting, an anti-friction roller rotatably mounted in the slidable casting and bearing and rolling upon said tread surface under normal conditions, said slidable casting being movable sufficiently to permit the 65 anti-friction roller to pass off of said tread surface and allow the roller to rotate about its own axis under excessive actuation of the bearing.

In witness that I claim the foregoing I 70 have hereunto subscribed my name this 24th day of March, 1915.

STACY B. HASELTINE.
